UNITED STATES PATENT OFFICE.

TIMOTHY A. CLANCY, OF HARTFORD, CONNECTICUT.

DESIGN FOR AN EMBLEM, BANNER, BADGE, PIN, OR SIMILAR ARTICLE.

55,844.

Specification for Design.

Patented July 20, 1920.

Application filed February 1, 1919. Serial No. 274,571. Term of patent 7 years.

To all whom it may concern:

Be it known that I, TIMOTHY A. CLANCY, a citizen of the United States, residing in Hartford, in the county of Hartford and State of Connecticut, have invented a new, original, and ornamental Design for an Emblem, Banner, Badge, Pin, or Similar Article, of which the following is a specification, reference being had to the accompanying drawing; forming part thereof, in which—

The figure is a face view of an emblem, banner, badge, pin or similar article showing my new design.

This design comprises an emblem, banner,

badge, pin or similar article embodying a body or ground round in form and having displayed thereon a round figure concentrically arranged with respect to the body, the two forming a circular band upon which are displayed portions of the outer edges of circular figures, the extreme edges of which touch the circular central figure. These figures are displayed in contrasting colors, as illustrated in the drawing.

I claim:—

The ornamental design for an emblem, banner, badge, pin or similar article, as shown.

TIMOTHY A. CLANCY.
